UNITED STATES PATENT OFFICE.

GEORGE C. KLEIN, OF AKRON, OHIO.

SHAFT-TUG.

SPECIFICATION forming part of Letters Patent No. 660,273, dated October 23, 1900.

Application filed May 28, 1900. Serial No. 18,247. (No model.)

To all whom it may concern:

Be it known that I, GEORGE C. KLEIN, a citizen of the United States, residing at Akron, in the county of Summit and State of Ohio, 5 have invented a certain new and useful Improvement in Thill-Loops, of which the following is a specification.

My invention has relation to improvements in thill-loops for single harness; and the object of my invention is to produce a new and improved loop that shall be neat and attractive in appearance and strong, durable in use, and peculiarly elastic.

To the aforesaid purpose my invention consists in the peculiar and novel construction, arrangement, and combination of parts hereinafter described and then specifically pointed out in the claim, reference being had to the accompanying drawings, forming a part of 20 this specification.

In the accompanying drawings, in which similar reference-numerals indicate like parts in the different views, Figure 1 is a side elevation of my improved thill-loop; Fig. 2, a 25 front view of the same, and Fig. 3 a central vertical section of the same.

This loop is primarily composed of rubber prepared for vulcanization and rubber-saturated duck similarly prepared, and when built 30 up these parts are simultaneously vulcanized to complete the article and cause them to cohere together. The arrangement of these parts constituting the completed loop is as follows:

35 Referring to the figures of the drawings, 1 is a ring of vulcanized rubber, which at the top and bottom extends beyond its general outer peripheral line to form projections, which projections inclose the lower bar of the 40 buckle 2 and the upper bar of the girth-loop 3. Within the ring 1 is a layer 4 of woven fabric, preferably duck, saturated with rub-

ber. About the outside of the ring 1 and following its contour to the places where the projections leave the outer peripheral line, 45 and rising with these projections and terminating at a line flush with the upper face of these projections, are a number of layers 5 of rubber-saturated fabric, and about the outer layer just described is a thin layer 6, which 50 similarly terminates flush with the outside of the said projections. At one side of this composite ring is a strap-loop 7, also of rubber, with a duck covering, built up and vulcanized with the other parts. On the united 55 ends of the different parts, at the top and bottom, are sheets 8 of rubber - saturated duck, similarly applied and vulcanized with the other parts.

Having thus described my invention, what 60 I claim, and desire to secure by Letters Patent, is—

As an improved article of manufacture, a thill-loop, having a lining of fabric and a surrounding ring of rubber extending beyond its 65 peripheral line at the top and bottom to form projections, of a buckle-bar and girth-loop bar respectively inclosed by said projections, a series of layers of fabric surrounding the outer line of said rubber ring excepting the 70 outer face of said projection, and an inclosing case of rubber terminating similarly with said layers of fabric, and caps of rubber-saturated fabric to cover the outside of said projections and the ends of said layers of fabric, 75 the whole arranged to be simultaneously united by vulcanization.

In testimony that I claim the above I hereunto set my hand in the presence of two subscribing witnesses.

GEORGE C. KLEIN.

In presence of—

JOSEPH DENGEL,
C. P. HUMPHREY.
